UNITED STATES PATENT OFFICE

2,288,011

TEETH SEPARATOR

Albert D. Mizzy, New York, N. Y.

Application November 23, 1940, Serial No. 366,835

5 Claims. (Cl. 32—64)

The present invention relates to teeth separators of the type used when separation is to be effected by the grinding off of a part of one or both of two adjacent teeth.

Heretofore such grinding has been effected by disks or strips of cord or like flexible material coated on one side with an abrasive substance. As is well known, such disks or strips commonly crumple and collapse under pressure on catching on a tooth or by wetting thereof, thus necessitating frequent replacements, and often cut the gum or other parts of the mouth when crumpled.

An object of the invention is a separator in which a blade of flexible material is positively held and secured taut against crumpling or collapse, and in which the mount of the blade may be such as will permit of easy and sure insertion and manipulation of the separator in any part of the mouth, and will provide for quick and easy interchange of blades.

A further object of the invention is a separator, of the character mentioned, which is of simple and durable structure; and the blade carrier of which may be of one-piece construction, producable in quantity at little cost by the stamping and bending of sheet metal.

Since the separator of the present invention permits of no crumpling of the blade, or of mouth injuries such as have heretofore resulted from crumpling of blades, less guard against cuts is required of the dentist; and, without risk of injury, the blade may be made of harder and tougher material than heretofore employed. It may, for instance, be of thin sheet steel or other metal, and thus be waterproof and durable. Such a blade may require no replacement during an operation other than when an abrading surface of different texture is desired. If of metal, the blade may be cleaned and re-used in subsequent operations, as are razor blades.

The above and other objects and features of the invention will hereinafter more fully appear in connection with the accompanying drawing in which:

Fig. 1 is a view in perspective of the assembled separator.

Fig. 2 is a bottom plan view of the structure shown in Fig. 1.

Fig. 3 is an end view looking from the left of Fig. 1.

Fig. 4 is an end view looking from the right of Fig. 1.

Fig. 5 is a view in perspective of the carrier frame or holder.

Fig. 6 is a side view of the assembly of blade and guard plate therefor.

Fig. 7 is a view of the blade and guard plates, unassembled.

Referring to the drawing, the device is shown as comprising a frame or holder 10 for an abrading blade 11, and for two guard plates 12 and 13, for the blade. The holder or carrier 10 (see Fig. 5) is an open ended, three sided frame or panel comprising a central reach 16 and two legs 14 and 15 protruding at right angles from the ends of the part 16. The part 16 is shown as of inverted U shaped cross section, and the side walls of the legs 14 and 15 are extensions of the front and rear walls of the part 16, cross-connected at their extremities by parts 17 and 18 which serve as abutments or supports for the blade 11 and guard plates 12 and 13. The legs 14 and 15 are thus of stirrup formation. When the blade and its guard plates are mounted in the holder or carrier 10, the abrading surface of the blade 11 is exposed through a window formed by the frame parts 14, 15 and 16 of the holder.

Ears or wings 19 and 20, one on each of the frame parts 14 and 15, at the left hand end of the holder 10, together form an expanded pressure surface for the thumb or finger of the operator, whereby to push the device as a whole longitudinally in one direction. It will be noted that the ears 19 and 20 are flared outwardly and laterally so as to define a pocket whereby to center the finger or thumb on the device and to prevent slip of the finger or thumb therefrom.

In Fig. 7 are shown the pair of side guards 12 and 13 for the abrasive blade 11. There are cut-outs in the plates 12 and 13 which register with and are of the same dimensions and shape as the cut-out formed by the three sides of the holder 10, so that the abrasive surface of the blade may be exposed through either side of the separator. Preferably, only one surface of the blade is abrasive: the other surface may be smooth. The plate 12, see Fig. 7, is shown as having pins 21 protruding from one face thereof, one near each end thereof, in the direction of the plate 13. The blade 11 has a pair of holes 22 therethrough adapted to register with and to receive the pins 21; and the plate 13 has a similar pair of holes 23 also in registry with the pins 21. The pins 21 are of length to pass through both the blade 11 and the plate 13 and to terminate flush with the outer surface of the latter. The fit of the pins 21 in holes 22 and 23 is such as to prevent shift of the blade with

respect to its guard plates and the pins 21 hold the blade taut when the device is assembled.

Each of the plates 12 and 13 is provided at its right hand end with an ear or wing, 24 and 25. These serve the same purpose at the right hand end of the assembled device as do the wings or ears 19-20 at the left hand end thereof. The device as a whole may therefore be held and operated by thumb pressure on the ears at one end of the same, and by opposed finger pressure on the ears at the other end thereof. The ears 24-25 on the blade guards also serve as means whereby the blade and guard assembly shown in Fig. 6 may be inserted into and removed from the frame piece 10 of Fig. 5.

As will be noted from the several figures of the drawing, the blade and guard assembly of Fig. 6 is of length, width and height to fit snugly in the frame member 10 between the roof, side walls and parts 17-18 of the latter. Frictional engagement of the guard plates 12-13 with the inside faces of the frame member 10 prevents accidental displacement of the blade and guard assembly from home position in the carrier 10. A push fit of the blade and guard assembly within the holder may suffice for this purpose. However, the side walls of the leg 14 may be slightly sprung to effect a clamping action thereof on the end of the blade and guard assembly, more securely to hold the latter against accidental longitudinal shift in the carrier.

If an abrasive blade becomes worn or when a blade of different abrasive texture is to be substituted for a blade previously in use, the blade assembly is removed as a unit from the carrier 10 by a pull on the ears 24-25. The guard plate 12 which carries the lock pins 21 is then lifted from the blade previously in use, and the newly selected blade, together with the guard 13, placed upon the pins 21; whereupon the new assembly is forced into the carrier 10 by pressure upon the ears 24-25.

The blade 11 is thin and flexible, and is preferably of sheet steel or other material which is hard, tough and waterproof. It is held taut in the carrier 10 by the pins 21 of the guard plate 22, and therefore cannot fold or crumple. Preferably only one side of the blade is abrasive: the other side is smooth, and so cannot hurt tooth, gum or tongue accidentally coming into contact therewith. All edges of the blade, except the free or working edge, thereof, are completely covered by legs 14 and 15 and part 16 of the carrier 10, and so cannot strike or cut the mouth. The blade, if of metal, cannot be injured in any proper use of the separator, and will normally require no renewal during an operation. If substitution of a blade of different abrading texture is desired during an operation, interchange of blades, as above indicated, may be effected easily and expeditiously. After use, the metal blade may be cleansed, sterilized, and re-used indefinitely in subsequent operations.

It will be understood that the drawing is illustrative of one embodiment of the invention only, and that, within the scope of the invention, widely varying styles of structure and assembly may be had.

I claim:

1. A tooth separator, comprising a blade having an abrading face, a guard for the blade hav-

ing means for positively holding the blade thereto, an open ended carrier having a base abutment for the assembled blade and guard and over which abutment the assembled blade and guard may be slid into the carrier from one end of the latter, and finger pieces at each end of the carrier whereby to effect a reciprocatory movement of the separator in the mouth, one of said finger pieces being on the carrier at one end of the latter and another of said finger pieces being on the guard at the other end of the carrier.

2. In a tooth separator, a blade having a pin hole therethrough and having an abrading face, and a guard comprising two plates adapted to be set against opposite faces of the blade, one of said plates having a pin hole therethrough for registry with the pin hole in the blade, and the other of said plates having a pin projecting therefrom for passage through the pin holes in the blade and opposite plate, and one of said plates being cut away for exposure of the abrading face of the blade.

3. In a tooth separator, a blade having an abrading surface, a guard for the blade having a detent thereon for interlockment of blade and guard upon face-to-face placement of blade against guard, and a carrier for the assembly of blade and guard having an abutment on which the assembly is seated by one edge thereof, a second abutment against which is set one face of said guard when the assembly is seated on the first abutment, and means on the carrier for holding the blade against the guard and for holding the assembled blade and guard against said second abutment, the carrier having an end opening through which the assembly may be introduced and moved longitudinally thereof over said first named abutment to its home, or operative, position in the carrier.

4. In a tooth separator, a blade having an abrading surface, a guard for the blade having a detent thereon for interlockment of blade and guard upon face-to-face placement of blade against guard, and a carrier for the assembly of blade and guard having an abutment on which the assembly is seated by one edge thereof, a second abutment against which is set one face of said guard when the assembly is seated on the first abutment, and resilient means on the carrier bearing yieldingly on the assembly for holding the blade against the guard and for holding the assembled blade and guard against said second abutment.

5. In a tooth separator, a blade having an abrading surface and a pin hole therein, a guard for the blade having a pin thereon for registration with the pin hole in the blade for interlockment of blade and guard upon face-to-face placement of blade against guard when said pin and pin hole are in registry, and a carrier for the assembly of blade and guard having an abutment on which the assembly is seated by one edge thereof, a second abutment against which is set one face of said guard when the assembly is seated on the first abutment, and means on the carrier for holding the blade against the guard and for holding the assembled blade and guard against said second abutment.
